UNITED STATES PATENT OFFICE.

CARL FRIEDRICH SCHLICKEYSEN, OF STEGLITZ, NEAR BERLIN, GERMANY.

CLAY PRESS OR MIXER.

No. 893,385.

Specification of Letters Patent.

Patented July 14, 1908.

Application filed December 21, 1906. Serial No. 348,941.

To all whom it may concern:

Be it known that I, CARL FRIEDRICH SCHLICKEYSEN, a subject of the German Emperor, and resident of Steglitz, near Berlin, Germany, have invented certain new and useful Improvements in and Relating to Clay Presses or Mixers, of which the following is a specification.

This invention relates to improvements in 10 clay presses or mixers designed for the purpose of mixing or kneading segregated lumps of clay into a homogeneous and uniform mass thereby rendering the same suitable for use in the manufacture of bricks, tubes 15 and other products formed of clay.

The device of this invention has to do with an improved character of machine of this type so constructed as to materially reduce wear of the parts and afford means whereby 20 material treated may be discharged in a condition suitable for use by a greatly reduced period of treatment and wherein a material reduction of motive power may be effected.

The invention will be more fully described 25 in connection with the accompanying drawing and will be more particularly pointed out and ascertained in and by the appended claims.

In the drawing: Figure 1 is a vertical section 30 view of one form of machine which embodies the main features of my invention. Fig. 2 is a sectional view of another form of the invention. Fig. 3 is a plan view of segments illustrating the different forms of 35 rings which may be used. Fig. 4 is a sectional view of a portion of the body of the machine shown in Fig. 1 drawn on an enlarged scale.

Like numerals of reference designate similar 40 parts throughout the different views of the drawing.

Considered generally the invention includes a body portion in which is formed a 45 passage through which the clay is forced from an inlet to a point of discharge and a plurality of mixers or kneaders disposed in said passage and serving in the performance of their function of mixing and kneading the clay to advance the same from said inlet to 50 the point of discharge. To this end the said kneaders or mixers are desirably given a helical or spiral formation in order to impart the requisite advancing movement but imparting such movement the kneaders also 55 rotate the clay and the same is closely

packed and compressed between the body portion and the kneaders and also between the spiral flights or blades of the kneaders resulting in the subjection to these parts of a powerful frictional contact thereby causing 60 the same to quickly wear out. It has also been found that the clay packs so tightly that very powerful driving means is required. Now it is the object of this invention to improve machines of this character and ob- 65 viate the foregoing defects by providing means for interrupting the rotary movement of the clay in its passage through the body portion and to so dispose and construct said means as to increase the mixing or kneading 70 action by causing the kneaders to alternately coöperate with the body portion and said means to thus increase the efficiency of the machine, in its mixing action, and thereby enhance the quality of the clay mixture dis- 75 charged.

By interrupting the rotary movement of the clay the tendency of the same to pack and clog is overcome while the tortuous and irregular course through which the clay is 80 forced causes a general shifting of the massed particles and uniform mixture which is highly desirable.

As shown, and referring more particularly to Fig. 1, the body portion is in the form of a 85 cylinder 2, having a flaring inlet portion 1 and an outlet 3. The kneaders or mixers are shown as mounted upon a shaft 14 which is centrally disposed within the cylinder 2 and may be mounted in suitable bearings (not 90 shown) and driven from any convenient source of power. The kneaders are indicated at 8, 9 and 10 and are preferably in the form of spirals which are spaced apart from each other a slight distance. The kneaders 95 are so disposed and proportioned with respect to the cylinder 2 as to coöperate with the wall thereof in the operation of kneading and mixing the clay, *i. e.* the peripheries of the kneaders are sufficiently close to the wall 100 of the cylinder so that the clay will engage the latter and will be mixed and kneaded by its contact with the kneaders and the wall of the cylinder.

In order to prevent a continuous rotary 105 movement from being imparted to the clay in its passage through the cylinder means are provided, preferably in the form of rings 4, 5, 6 and 7, which are disposed adjacent the spaces formed between said kneaders and 110

which project outwardly from the wall of the cylinder 2 toward said kneaders in a manner to reduce the area of the passage through which the clay is forced. As the clay is forced downwardly between the kneaders and the wall of the cylinder it engages the rings and the kneaders thereupon cease to coöperate with the wall of the cylinder 2 and coöperate with the said rings in forcing the clay there-through and thus it will be seen that the kneaders act alternately, on a given portion of the clay, in coöperation with the wall of the cylinder 2 and said rings. Owing to the fact that the rings are interposed in the spaces formed between the kneaders and as the same act downwardly upon the clay forcing the same against said rings the latter serve to interrupt the rotary movement of the clay in its downwardly advancing movement. It will also be understood that inasmuch as the clay is given a uniform movement while it is passing between the rings and as the passage at such points affords a relatively greater area than at points adjacent the rings the clay will, when it reaches the rings, be forced there-through at a relatively increased speed with respect to its speed between said rings and this feature will materially increase the efficiency of the rings in interrupting or preventing rotary movement of the clay. When the clay has been compressed by said rings and has passed there-through it will immediately be permitted to expand into the relatively increased space below the rings and will be immediately engaged by the next kneader or mixer and advanced toward the point of discharge.

In order to further increase the capacity of the rings in preventing rotation of the clay the same may be provided on their inner margins with notches as indicated at 13 and arranged in parallel relation. In this form of ring the clay in its passage is forced into said notches and the same not only serve to further retard the rotary movement but they also serve to shift the particles of massed clay and further increase the mixing efficiency of the machine.

In some embodiments of the machine designed for certain classes of work it may be desirable to bevel the rings in order that the compressive action due to the passage of the clay through said rings may be more gradual and to this end it has been found that the best results are obtained by beveling the rings so that the beveled portion faces toward the inlet and in a direction opposite to the course of the clay as clearly shown in Figs. 1 and 4. In cases where it is desirable to insure immediate engagement of the kneaders, located below the rings, with the clay passing there-through the rings may be beveled on their lower sides in the manner shown in Fig. 2.

65 In the embodiment shown the inlet por-

tion 1 is provided with a kneader having spirals 11 and 12 in order to insure a uniform and constant supply to the machine and at the point of discharge the machine is conveniently provided with a spirally formed 70 delivery member 15.

In the form shown in Fig. 2 the cylinder 2 is horizontally disposed but in other respects this form of the machine is substantially the same structurally and in operation as the machine shown in Fig. 1.

I claim:

1. A clay press comprising in combination, a cylinder, a rotary shaft therefor, helicoidal kneaders carried by said shaft and spaced 80 apart from each other, and rings secured to said cylinder adjacent the spaces formed by said kneaders, said rings being notched adjacent said spaces and having upwardly inclined portions projecting above said spaces. 85

2. A clay press comprising in combination, a cylinder, a rotary shaft mounted in said cylinder, a plurality of helicoidal kneaders arranged on said shaft and spaced apart from each other, and rings secured to the inner 90 wall of said cylinder adjacent the spaces formed by said kneader, said rings being beveled outwardly and upwardly.

3. A clay press comprising in combination, a cylinder, a rotary shaft mounted in said 95 cylinder, a plurality of helicoidal kneaders arranged on said shaft and spaced apart from each other, and rings secured to the inner wall of said cylinder and projecting into the spaces formed by said kneaders, said rings 100 being beveled toward said cylinders in opposite directions.

4. A clay press or mixer comprising in combination, a cylinder, a shaft therefor, a plurality of rotary kneaders mounted upon 105 said shaft and spaced apart from each other and coöoperating with the wall of said cylinder in the mixing and kneading of the clay, and notched rings detachably secured to said cylinder adjacent the spaces formed between 110 said kneaders and projecting into said spaces whereby the rotary movement of the clay may be interrupted.

5. A clay press or mixer comprising in combination, a body portion provided with a 115 passage for the clay, a plurality of rotary kneaders adapted to engage the clay and advance the same in said passage, said kneaders being spaced apart from each other, and rings detachably secured adjacent said 120 spaces and projecting into the same whereby the passage in said body portion is restricted and the rotary movement imparted to the clay by said kneaders is interrupted.

6. A clay press or mixer comprising in combination, a body portion provided with a 125 passage for the clay, a plurality of rotary kneaders engaging the clay and advancing the same in said passage, said kneaders being spaced apart from each other, and removable 130

means located adjacent said spaces and projecting into the same thereby restricting the passage in said body portion and interrupting the rotary movement imparted to the clay
5 by said kneaders, said kneaders coöperating with the wall of said body portion and with said means in mixing the clay.

In testimony whereof I have hereunto set my hand, in presence of two witnesses.

CARL FRIEDRICH SCHLICKEYSEN.
